UNITED STATES PATENT OFFICE.

GLADYS MARY DASH, OF SOUTH TOTTENHAM, LONDON, ENGLAND.

LOOFAH MATERIAL.

No Drawing. Application filed January 2, 1926, Serial No. 79,033, and in Great Britain January 21, 1925.

In the ordinary commercial use of loofah a large amount of waste occurs for example in the manufacture of insoles for boots as the insole is cut from the loofah and much 5 of the unused part is thrown away as waste, also loofahs which by reason of surface damage or inferior quality are unsuitable for manufacturing purposes.

According to this invention I break or 10 tear loofah, more particularly waste loofah or loofahs of inferior quality, care being taken not to cut the loofah into small pieces or to press it under heavy pressure, as cutting and pressing cause loofah to lose its 15 properties, and I so regulate the process of breaking or tearing that the product may be either a fine or a coarse loofah down. The loofah may be broken or torn in a breaking or tearing machine which usually comprises 20 cylinders with tearing teeth; a suitable machine may be bought on the open market and is known as a hard waste opening machine.

Loofah down may be used for any purpose 25 such as socks and insoles of boots, stuffings for mattresses, cushions, and as a sole filler for footwear, and for any like purposes to which fibrous materials are put.

In the manufacture of insoles, mattresses or cushions, a bag of textile material or 30 loofahs or any other suitable material is filled with loofah down and enclosed with a row of stitching. The down is evenly distributed in the bag and is then quilted. A sole or other article is cut out from the filled 35 bag and is then sewn round the edge in order to hold the material together.

A stuffing of loofah down is found superior to hair and flock as is now employed, in that it is light, resilient and odourless, 40 and does not lose its properties when subjected to damp.

What I claim is:—

1. The process of making loofah down from pieces of loofah which consists in tearing apart the individual uncut fibres of said 45 pieces until they are loosely related to each other.

2. As an article of manufacture loofah down having the individual uncut fibres in 50 very loose relation to each other, thus forming a light resilient material.

In testimony that I claim the foregoing as my invention I have signed my name this 15th day of December, 1925.

GLADYS MARY DASH.
